PEDICURE UNIT

Eloise N. Johnson, Dallas, Tex.

Application September 8, 1958, Serial No. 52,557

Term of patent 14 years

(Cl. D86—10)

FIG. 1

Fig. 1 is a front perspective view showing the top and left side of a pedicure unit embodying my new design, the right side being substantially like the left side shown,

Fig. 2 is an enlarged top plan view thereof, and

Fig. 3 is a fragmentary view in elevation of the upper portion of the left side of the pedicure unit.

The dominant features of my design reside in the full line portion of the drawing.

I claim:

The ornamental design of a pedicure unit, substantially as shown and described.
